MUSICAL INSTRUMENT MOUTHPIECE

Filed April 19, 1926

FIG. 1

FIG. 2

FIG. 3

INVENTOR
Nelson B. Bailey

BY Charles S. Evans
ATTORNEY

UNITED STATES PATENT OFFICE.

NELSON B. BAILEY, OF SAN FRANCISCO, CALIFORNIA.

MUSICAL-INSTRUMENT MOUTHPIECE.

Application filed April 19, 1926. Serial No. 102,865.

My invention relates to musical instruments, and particularly to mouthpieces for vibrating for reed instruments.

One of the objects of my invention is to provide a novel mouthpiece which will obviate the hard, reedy tone common to vibrating reed instruments, and will permit a very clear and sweet tone on the instrument with which it is used.

10 Another object of the the invention is the provision of a mouthpiece that may be made to mute the tone of the instrument with which it is used so that a student may practice without disturbing others around him.

15 The invention possesses other objects and features of advantage some of which, with the foregoing, will be set forth in the following description of the preferred form of my invention which is illustrated in the drawings 20 accompanying and forming part of the specification. It is to be understood that I do not limit myself to the showing made by the said drawings and description, as I may adopt variations of the preferred form within 25 in the scope of my invention as set forth in the claims.

In the drawings:

Figure 1 is a side elevation of a musical instrument mouthpiece embodying my invention.

Figure 2 is a cross sectional view, the plane of section being taken on the line 2—2 of Figure 1.

Figure 3, a detail, is a plan view of the pad 35 or cushion.

Broadly my invention comprises a mouthpiece of the vibrating reed type such as is used on a saxophone or clarinet. To eliminate undesirable vibrations a cushioning pad 40 is provided between the reed and the bed of the mouthpiece, and is preferably permanently secured to the bed.

I have discovered that by interposing such a pad or cushion between the reed and the bed, not only is the instrument easier to blow, but the tone of the instrument is greatly improved in so far as it is clearer and sweeter than that heretofore attained, except by the exercise of great skill.

50 The exact theory underlying these improvements is not clearly understood, but it is probable that the improved tone is due to a dampening effect of the pad upon vibrations which are set up in the body of the instrument when the reed is mounted in direct contact therewith.

Furthermore a greater range of adjustment of the reed, relative to the bed is obtained when an elastic or yieldable pad is interposed therebetween, which permits exact adjustment for tone quality.

Referring to the drawings:

In Figure 1, I have shown a mouthpiece particularly adapted for use with a saxophone. The mouthpiece comprises a head 2, 65 provided with a tapering end 3, for engagement with the lips of the player, and at the other end with a neck 4 whereby the mouthpiece is mounted on the body 6 of the saxophone (only the end of which is shown). 70 The bed 7 of the mouthpiece is provided with a dovetail groove which extends around the opening in the upper face of the tapered end, and in which is engaged a corresponding dovetail bead 8 formed on the underside of 75 a pad or cushion strip 9, preferably of soft rubber or other yieldable shock absorbing substance. Since the pad is soft and readily deformable it may be forcibly crowded into the groove, and once seated it remains securely in position.

The tone and volume of the instrument can be controlled by the size and density of the cushioning pad. For example, a thin hard layer of rubber will produce a superior tone 85 quality without materially lessening the volume, and for orchestra or concert playing this type of mouthpiece will be found desirable. On the other hand, if it is desirable to mute the volume of an instrument, a thick soft 90 cushion may be used and this produces a very soft and mellow tone. This latter form is particularly adapted for use by students who have to practice in a hotel or an apartment house, for the volume and tone can be so 95 muted and mellowed that it can hardly be heard in an adjoining room.

A reed 11 of usual construction, is mounted on the bed 7 over the cushion 9, and is adjustably held in place thereon by means of the usual clamp ring 12 which is secured by the two thumb screws 13. Because of the yieldability or elasticity of the cushion 9, on which the reed rests, relative movement of the thumb screws permits the reed to be rocked sufficiently to make minute adjustment thereof relative to the bed, so that a tone becomes easily attainable by a beginner, which heretofore only much practice could give.

I have shown the cushion dovetailed to 110 the mouthpiece, but it is to be understood that it may be vulcanized or cemented to the

mouthpiece, or secured in any other suitable way.

I claim:

1. A wind instrument mouthpiece comprising a bed, a reed for said bed, and an elastic pad interposed between the entire reed and said bed.

2. A wind instrument mouthpiece comprising a bed, a reed for said bed, an elastic pad interposed between the entire reed and said bed to prevent vibrations of the reed being transmitted to the instrument, and means for clamping said reed to said bed.

3. A wind instrument mouthpiece comprising a bed, a reed for said bed, an elastic pad interposed between said reed and said bed,

and a plurality of clamping means spaced apart for independently clamping said reed to said bed.

4. A reed instrument mouthpiece comprising a bed having a groove, an elastic pad mounted on said bed and provided with a bead engaging said groove, a reed engaging said elastic pad, and means for adjustably securing said reed to said pad. 20

5. A reed instrument mouthpiece comprising a bed, a reed for said bed, and a soft rubber cushion dovetailed to said bed and interposed between said bed and said reed. 25

In testimony whereof, I have hereunto set 30 my hand.

NELSON B. BAILEY.
